UNITED STATES PATENT OFFICE

JAMES J. MURPHY, OF TERRYVILLE, CONNECTICUT, ASSIGNOR TO EAGLE LOCK CO., OF NEW YORK, N. Y., A CORPORATION OF CONNECTICUT

LOCK

Application filed February 21, 1929. Serial No. 341,614.

My invention relates to locks, and has special reference to locks of the shackle type in which the arms of the shackle are adapted to be inserted through apertures in the lock case and adjustably held therein by lock mechanism.

The principal object of my invention is to provide a lock of the shackle type which is of simple, cheap and strong construction, and which otherwise meets all the requirements of a lock of this character.

This and other objects of the invention and features whereby they may be attained, will be clearly understood from the following description and accompanying drawings, in which:

Figure 1 is a front view, partly in section, of the lock with a part of the casing thereof removed so as to show the lock mechanism, this mechanism being shown by full lines in unlocked position and by broken lines in locked position;

Figs. 2, 3 and 4 are sectional views taken on the lines 2—2, 3—3 and 4—4, respectively, of Fig. 1;

Fig. 5 is a detail view showing the several key-operable tumblers of the lock in front elevation, the tumblers being removed from the lock and separated; and

Fig. 6 is a front view of a key for the lock.

My improved lock, as illustrated in the drawings, is provided with the usual shackle 2 having the inner sides of its arms provided with ratchet teeth 4, and a lock case 6 having vertical apertures therein through which the arms of the shackle are adapted to be inserted. The lock case is made in two parts arranged one back of the other, and secured together by means of posts 8 integral with one of the parts and riveted to the other part.

The lock mechanism comprises two dogs 10 that are mounted to slide in a horizontal guideway formed by a rib 12 on the back part of the lock case, and by opposed ribs 14 on the two parts of the lock case. Each dog 10 is provided with a shank portion 16 and a head 18, the shanks of the two dogs being arranged one back of the other in sliding engagement and the heads 18 extending transversely of the lock case, each head extending

over the inner end of the shank of the other dog. The two dogs are pressed outwardly by means of springs 20 coiled about pins 22, the ends of each spring being mounted in sockets in the inner end of the shank of each dog 55 and the head of the other dog. The underside of the heads of the dogs 10 are flat so that when the dogs are shifted into engagement with the ratchet teeth on the arms of the shackle 2, the shackle is prevented from being 60 withdrawn. The top side of the head of each dog is curved so as to permit the arms of the shackle, even when the dogs are in their projected positions, to be inserted the desired distance into the lock case, the springs 22 permitting the necessary retraction and projection of the dogs during the insertion of the shackle.

The inner side of the shank of each dog 10 is provided with a slot 24 which receives an 70 upwardly projecting tongue 26 formed on the upper end of a key-operable tumbler 28, the two tumblers 28 being pivotally mounted at their lower ends on a pin 30 secured to the back part of the lock case. The two tumblers 75 28 are provided with suitable openings 32 for receiving a key 34, so that upon turning the key in a clockwise direction the tumblers are turned in opposite directions and through their tongue and slot connections with the 80 respective dogs serve to retract the dogs from holding engagement with the arms of the shackle, thus unlocking the shackle to permit it to be removed. Upon turning the key in a counter-clockwise direction the tumblers 85 28 are turned so as to project the dogs 10 into position to engage the teeth of the shackle.

In addition to the tumblers 28, the lock mechanism is provided with a tumbler 36 having its key-receiving opening 38 so 90 shaped as to limit the turning movement of the key to ninety degrees. Also, the lock mechanism is provided with tumblers 40 having their key-receiving openings so formed as to permit removal of the key only when the 95 dogs are in locking position.

The key is guided into operative engagement with the tumblers by means of a guideway or key-hole formed in a flanged disk 42 extending through an aperture in the front 100

wall of the lock case, the key-hole being provided with the usual swivel cover 44.

With this construction it will be apparent that to unlock the lock so as to permit removal of the shackle, the key is given a quarter turn in a clockwise direction which through the tumblers 28 retracts the dogs from the teeth of the shackle. To move the dogs into locking position, the key is given a quarter turn in the opposite direction whereupon the key may be removed.

The provision of the tumblers 36 and 40 for respectively limiting the turning movement of the key and preventing the key from being removed except when the dogs are in locking position, insures that the shackle will be locked in position when inserted in the lock and the key removed.

Arms 46 of spring sheet metal, transversely curved as shown, have their upper portions riveted at 48 to the back part of the lock case and have their lower free ends normally projecting into the path of the shackle arms. When the shackle is inserted through the proper end of the lock case as shown in Fig. 1, the ends of its arms will force the spring arms 46 outwardly so as to permit them to slide over said spring arms. In case, however, it were attempted to insert the shackle into the wrong end of the lock case, the ends of the shackle arms would strike the free ends of the spring arms 46 and thus further insertion of the shackle arms would be positively prevented.

As will be evident to those skilled in the art, my invention permits various modifications without departing from the spirit thereof or the scope of the appended claims.

What I claim is:

1. A lock of the class described having, in combination, a shackle, a lock case through which the arms of the shackle may be inserted, dogs adapted to be shifted into and out of engagement with the shackle arms, key operable tumblers for thus shifting said dogs, and tumblers serving to prevent removal of the key except when the dogs are in shackle-engaging position.

2. A lock of the class described having, in combination, a shackle, a lock case through which the arms of the shackle may be inserted, dogs adapted to be shifted into and out of engagement with the shackle arms, two key operable tumblers mounted in the lock case and each adapted to be moved in opposite directions upon turning the key in opposite directions respectively, the two tumblers being thus moved simultaneously but in opposite directions, and means comprising tongue and slot connections between said dogs and tumblers for shifting said dogs into and out of engagement with the shackle arms upon turning the key in opposite directions, respectively, and tumblers serving to prevent re-

moval of the key except when the dogs are in shackle engaging position.

3. A lock of the class described having, in combination, a shackle, a lock case through which the arms of the shackle may be inserted, dogs adapted to be shifted into and out of engagement with the shackle arms, key operable tumblers pivotally mounted in the lock case and each adapted to be turned in opposite directions upon respectively turning the key in opposite directions, the two tumblers being thus turned simultaneously but in opposite directions, and means comprising tongue and slot connections between said dogs and tumblers for shifting said dogs into and out of engagement with the shackle arms upon respectively turning the key in opposite directions, and springs tending to shift said dogs into engagement with said arms, and tumblers serving to prevent removal of the key except when the dogs are in shackle engaging position.

4. A lock of the class described having, in combination, a shackle, a lock case through which the arms of the shackle may be inserted, dogs adapted to be respectively shifted into and out of engagement with the shackle arms, a plurality of key operable tumblers pivotally mounted in the lock case, each of two of said tumblers being adapted to be turned in opposite directions upon turning the key in opposite directions, said two tumblers being thus turned simultaneously but in opposite directions, and means comprising tongue and slot connections between said dogs and tumblers for shifting said dogs into and out of engagement with the shackle arms upon turning the key in opposite directions, other of said tumblers serving to prevent removal of the key except when the dogs are in shackle engaging position.

5. A lock of the class described having, in combination, a shackle, a lock case through which the arms of the shackle may be inserted dogs adapted to be respectively shifted into and out of engagement with the shackle arms, a plurality of key operable tumblers pivotally mounted in the lock case, each of two of said tumblers being adapted to be turned in opposite directions upon turning the key in opposite directions, said two tumblers being thus turned simultaneously but in opposite directions, connections between said dogs and tumblers for shifting said dogs into and out of engagement with the shackle arms upon turning the key in opposite directions, other of said tumblers serving to prevent removal of the key except when the dogs are in shackle engaging position.

In testimony whereof, I have signed my name to this specification this 28th day of January, 1929.

JAMES J. MURPHY.
